Des. 221,841
Patented Sept. 14, 1971

221,841

MEAT CUBING DEVICE

Irene Saxton, 250 W. 100th St.,
New York, N.Y. 10025

Filed June 29, 1970, Ser. No. 23,742

Term of patent 3½ years

Int. Cl. D15—08

U.S. Cl. D11—1

F I G . 1

F I G . 2

FIG. 3

FIG. 4

FIG. 1 is a front perspective view of a meat cubing device embodying my new design;

FIG. 2 is a side elevation view thereof;

FIG. 3 is a top plan view thereof; and

FIG. 4 is a front elevation view thereof.

What I claim is:

The ornamental design for a meat cubing device, substantially as shown and described.
